UNITED STATES PATENT OFFICE.

JOHN PEALE DE L'EAU, OF BETTERAVIA, CALIFORNIA.

DENTAL-FLOSS HOLDER.

1,171,177.

Specification of Letters Patent.

Patented Feb. 8, 1916.

Application filed March 31, 1915. Serial No. 18,294.

To all whom it may concern:

Be it known that I, JOHN P. DE L'EAU, a citizen of the United States, and a resident of Betteravia, in the county of Santa Barbara and State of California, have invented 5 certain new and useful Improvements in Dental-Floss Holders, of which the following is a specification.

My invention relates to means for cleansing the spaces between the teeth of a person by the removal of particles of food and the like, through the medium of what is known as dental floss, or the equivalent, and one of 10 the main objects it to provide means serving the dual purpose of containing the floss and, when desired, holding a suitable length thereof in operative position for use.

A further object is to maintain the floss in a cleanly manner.

20 A further object is to provide instantly actuated means for holding a length of the floss in position for use.

A further object is to provide means for 25 cutting off the used length.

A further object is to provide ready means for refilling the container after the supply of floss therein has been exhausted; and further objects are to provide such means which are simple in construction and operation, very compact, particularly adapted for 30 a pocket or hand-bag, and comparatively inexpensive.

My invention is fully described in the following specification, of which the accompanying drawings form a part, in which like reference characters refer to like parts in each of the views, and in which:—

Figure 1 is a longitudinal section taken through my device, ready for use; Fig. 2 is a similar view thereof, partially in elevation, in closed position; Fig. 3 is a plan view thereof; Fig. 4 is an enlarged end view of one of the arms shown in Figs. 1 and 2; and Fig. 5 is a side view of the detail shown 45 in Fig. 4.

In the drawings forming a part of this application I have shown a tube 6 having a cap 7 shown telescoped on the lower end thereof in Fig. 1 provided with a flange 8 adapted to be engaged by spring clips 9 on the opposite end of the tube or barrel 6 when said cap is reversed as shown in Fig. 2, when the device is not in use.

The barrel 6 has a fixed pin 10 closely 55 adjacent its upper end which serves as a pivot for two tubular arms 11 and 12 pro-

vided with segmental plates 13 at their lower ends adapted to be engaged by the clips 9, as shown in Fig. 1, to hold said arms in desired angularity with respect to the axis of 60 the barrel 6, but permitting said plates to be disengaged when the device is to be closed, said plates jointly serving as a closure for the upper end of said barrel when the device is in use, as shown in Fig. 3. 65

The arm 11 is provided with a tapered, screw-threaded, portion 14, a reduced portion 15, and a disk 16 secured thereon in fixed position, a washer 17 being slidable on said reduced portion 15, and an internally threaded sleeve 18 being threaded on the taper portion 14, and, when said sleeve 18 is reversely turned to move downwardly on said arm 11, the washer 17 moves away from the disk 16; when this sleeve rotation 75 is reversed, the washer is forced into close engagement with the disk 16, the taper thread being provided for quick separation of the washer and disk and quick engagement thereof. The outer end of the arm 12 80 is similarly threaded at 19 and preferably longitudinally slotted whereby, when a sleeve 20 thereon is screwed upwardly, the tongues formed by said slots are brought together to bind the floss or other thread 21, 85 therebetween in the manner of a chuck and, when said sleeve is reversely screwed, the thread is released and may be drawn outwardly of the arm 12.

The floss or thread is usually provided 90 in a cylindrical form, as on a spool or tube, and I prefer to arrange this coil 22 within a vial 23 of the approximate diameter of the interior of the barrel 6, a removable pin 24 serving to imprison said vial, though 95 permitting its ready removal, as for substitution of a new coil or spool of floss or other thread.

The floss 21 is led upwardly through the arm 12 and thence between the washer 17 and disk 16 previously separated to admit the floss, after which the sleeve 18 is moved to bind the floss between said washer and disk, and the sleeve 20 is actuated to bind the floss in the arm 12, the latter binding 105 being preferably first performed, although I may set the chuck to permit the floss to pass therethrough against sufficient frictional resistance to hold the length between the two arms in stretched condition for use. After 110 use, this used length may be drawn between the washer and disk, released for the pur-

pose, and cut off by means of a cutting blade, preferably V-shaped, shown at 25, Figs. 4 and 5, projecting from the disk 16; the arms 11 and 12 may now be forced toward each other manually, thereby disengaging the plates 13 from the clips 9, and the cap 7 reversed into the position shown in Fig. 2, the device now being ready for storage, as in a pocket or the like.

10 It will thus be seen that I provide a container for dental floss wherein said floss is maintained in a cleanly manner, and I also provide the arms 11 and 12 between which the floss is held under desired tension, for 15 use, and I further provide a cutter to remove the used length of floss.

My invention is very simple, though highly efficient, and, while I have shown a present preferred form of embodiment of 20 my invention, I do not limit myself thereto, but may make changes thereover, within the scope of the following claims, without departing from the spirit of my invention or sacrificing its advantages.

25 Having fully described my invention, what I claim as new, and desire to secure by Letters Patent, is:—

1. A device of the class described, comprising a container for a supply of dental 30 thread, a cap adapted to be reversed thereon, means for holding said cap in place, two arms in pivotal connection with said container, a plate on each arm engaged by the respective cap holding means and jointly forming a cover for said container when said cap is reversed, one of said arms being tubular to permit the passage of said thread, and means for tensionally holding a portion 35 of said thread between the outer ends of said arms.

40 2. A device of the class described, com-

prising a tube, a removable cap therefor, a vial in said tube, adapted to contain a supply of dental thread, two arms in pivotal connection with said tube through one of which said thread is passed, means for holding said arms in spread positions, and means for detachably holding the end of said thread on the other of said arms. 45

3. A device of the class described, comprising a tube, a removable cap therefor, a vial in said tube, adapted to contain a supply of dental thread, two arms in pivotal connection with said tube and through one of which said thread is passed, means for holding said arms in spread positions, 55 means for clamping said thread in the arm through which it is passed, and means for detachably holding the end of said thread on the other of said arms.

4. A device of the class described, comprising a container for a supply of dental thread, a cap adapted to be reversed thereon, means for holding said cap in place, two arms in pivotal connection with said container, a plate on each arm engaged by the 60 respective cap holding means and jointly forming a cover for said container when said cap is reversed, one of said arms being tubular to permit the passage of said thread, and means for tensionally holding a portion 65 of said thread between the outer ends of said arms. 70

In testimony whereof I have signed my name to this specification in the presence of two subscribing witnesses.

JOHN PEALE DE L'EAU.
